IMAGE TRANSMISSION APPARATUS

Hermann Robeck, Berlin, Germany, assignor to
 Siemens & Halske, Aktiengesellschaft, Berlin-
 Siemensstadt, Germany, a corporation of Ger-
 many

Application August 19, 1931, Serial No. 558,162
 In Germany September 1, 1930

3 Claims. (Cl. 178—8)

This invention relates to a process for the transmission and recording of pictures, signs or the like, in which the movable parts at the transmission and receiving end are constituted by 5 rotatable writing surfaces or the like driven and released entirely independently of each other, an independence of the receiving process from the starting of the transmitting apparatus being achieved.

10 Such apparatus are locally synchronized, that is to say, at both ends means are provided such as standard tuning forks, pendulums or the like by means of which the speed of the rotating writing surfaces can be controlled and main- 15 tained either constantly the same at both ends or constantly reduced or increased by a multiple (integer number). The standard tuning means are compared with each other at long intervals of time. For the reception of complete pictures it 20 is moreover necessary to synchronize the moments at which the writing surfaces are released. For this purpose periodically recurring current impulses have been frequently used hitherto; these impulses being sent out from the trans- 25 mitter end and caused to act at the receiving end.

In the process according to the invention, the devices are no longer brought in step, but in spite of that, one picture is produced at the receiving end which does not appear cut up or interrupted by paper clamping joints, stops or the like. For this purpose the process of transmission or of reception at both ends or at one end only is shifted in time, the feeling or writing being done doubly.

In the case of continuously travelling rotat- 40 ing surfaces, at the transmitting end pictures are used which at the outside reach half-way round the circumference, whilst at the transmitting end two writing pencils or stylus which are displaced to the extent of at least one picture width, are caused to explore the writing surface simulta- 45 neously. The stylus are preferably displaced by an angle of 180° relatively to each other.

If the fixing or clamping slot, for instance of a cylindrical drum, at the receiving end is in the centre of a picture, it is true that this picture will appear cut up, but the adjoining picture will be complete.

In systems which work on the start-stop sys- 50 tem, the stop is used as is well known after every revolution as the synchronizing means and is released from the transmitter end. In the case 55 of local synchronizing, this stop can also be used

in which case it is released by the said local synchronizing device.

At the receiving end of these stop systems two writing surfaces rotating with the same speed, the stops and stylus of which are displaced in time relatively to each other, can be simultaneously explored or written upon. The picture at the transmitting end must not exceed the time of rotation between the end and beginning of two successive stops of the receiving end. The most 10 favorable plan is therefore to set these stops at 180° to the rotating surface, as in this case the largest possible picture dimensions can be transmitted.

An increase of the picture up to half the cir- 15 cumference of the surface of rotation is obtained by arranging at the transmitting end two pictures arranged behind each other, whilst the receiving ends are also caused to work with two writing surfaces, the screens, screen contacts 20 or the like of which, as well as their stylus, displaced to the duration of at least one stop, but at the outside of one revolution, release the writing surface.

Also, in this case, the simplest method is to 25 choose the release with a time difference of half a revolution as in this way, for instance in the case of pendulums, stops are obtained by means of contacts at both sides of their deflections without any complicated devices. It is, however, pos- 30 sible to use only one writing surface at the receiving end by feeling or exploring the transmitting end also with a picture which comprises half a circumference of the writing surfaces less 1/2 stop. Two stylus are then used at the receiving end 35 connected in parallel, which therefore write si- multaneously and are displaced relatively to each other to the extent of one picture width.

In the accompanying drawings,

Figures 1 to 3 are diagrammatic representa- 40 tions of the start-stop system;

Figures 4 and 5 are diagrammatic illustrations of a transmitter and a receiver respectively con- 45 structed in accordance with the principles of the invention;

Figure 6 represents a sheet bearing an image for use with the transmitter shown in Figure 4; and

Figure 7 represents the corresponding sheet bearing the image reproduced by the receiver 50 shown in Figure 5.

Referring more specifically to the drawings and with particular reference to Figures 1 to 3 inclusive thereof, it will be noted that 2a is the time of the revolution of a rotating surface, b 55

the duration of stop, c the lead or the lag of the receiver relatively to the transmitter. The systems are indicated in the lines E I and E II (of the receiver), those of the transmitting end in the lines S. X and Y are the times of the corresponding pictures.

Let it be assumed that the line S is displaced relatively to the line E I or E II, then c will be varied thereby. The fields X and Y are then projected downwards on the lines E I or E II and in each case, at least one complete picture will be obtained.

In Figure 1, the displacement of the receivers relatively to each other is equal to

$$15 \quad a + \frac{1}{2}b \quad (180^\circ)$$

and the picture in the transmitter

$$S \text{ equal to } a - \frac{1}{2}b$$

20 that is to say, equal to the time between the end and the beginning of the stops of E I and E II.

In Figure 2, the displacement is equal to b , that is to say equal to one stop. In the transmitter S there are two identical pictures of the width a . In Figure 3, in the transmitter S two rotating take-off or feeler contacts V Z are connected in parallel and displaced to the width of one picture, and the width of the picture in the

30 transmitter is

$$a - \frac{1}{2}b.$$

In Figures 4 to 7, the transmitter and receiver have been drawn diagrammatically for the case in which the writing surfaces 1 and 1a of the 35 two apparatus are equal in size and have a circumference equal to $2a$. The receiver lags behind the transmitter by c . Two stylos 3 and 4, displaced relatively to one another by 180° , are arranged on the circumference of the transmitter writing surface. The picture reproducer of the receiver is shown at 2, while 5 and 6 are the brushes situated on the axis of the apparatus and forming the second terminals. The arrows 7 show the direction of rotation. The copy sheet 40 clamped on the transmitter is therefore explored

twice at the transmitter and is recorded twice at the receiver 1a, being recorded once as an intact picture which is displaced by an amount c relatively to the lower edge of the writing surface, while the second picture is cut by the edge 5 of the sheet.

I claim:—

1. In apparatus for transmitting and recording images, the combination with a transmitter comprising means for scanning each transverse element of an image to produce corresponding electrical impulses, of a recording device for receiving the impulses, and means for causing said device to record each transverse element of the image twice in succession in adjacent relation 15 and spaced in the direction of scanning to produce duplicate images, whereby one of the two recorded images will be uninterrupted.

2. In apparatus for transmitting and recording images, the combination with a transmitter comprising 20 means for scanning each transverse element of an image twice in succession to produce corresponding electrical impulses, a recording device for receiving the impulses, and means for causing said device to record each transverse element of the image twice in succession in adjacent relation 25 and spaced in the direction of scanning to produce duplicate images, whereby one of the two recorded images will be uninterrupted.

3. In apparatus for transmitting and recording 30 images, the combination with a transmitter comprising a rotating drum for supporting an image record, means for scanning each element of the image record to produce corresponding electrical 35 impulses, a recording device comprising a rotating drum for supporting an image record receiving element, and means cooperating with said record receiving element and responsive to the transmitted electrical impulses for recording each transverse element of the image twice in 40 succession in adjacent relation and spaced in the direction of scanning to produce duplicate images, whereby one of the two recorded images will be uninterrupted.

45 HERMANN ROBECK.
